FRANK M. CROWELL, OF TULSA, OKLAHOMA.

SUPPORT FOR WELL CASINGS.

Application filed May 13, 1926. Serial No. 108,924.

In deep producing oil and gas wells which utilize casing, or tubing, as a conduit through which the production comes to the surface, where it is necessary to suspend 5 all or part of the weight of the casing, or tubing, on clamps placed under a collar, or coupling, at the top of the hole instead of resting the entire weight on the bottom of the bore, it is often more convenient to use 10 a separate ring or slips for gripping the tubing or casing.

The present invention provides a tubing, or casing support, or clamp embodying in a single structure, a casing ring and casing 15 clamp or a tubing ring and tubing clamp and slips, said structure being preferably formed in similar sections which are clamped about the tubing or casing and recessed to receive a packing to insure a close joint and 20 prevent any air leak.

While the drawings illustrate a preferred embodiment of the invention, it is to be understood that in adapting the means to meet specific needs and requirements, the 25 design may be varied and such other changes in the minor details of construction may be resorted to within the scope of the invention as claimed, without departing from the spirit thereof.

For a full understanding of the invention and the merits thereof, reference is to be had to the following description and the drawings hereto attached, in which

Figure 1 is a detail view illustrating an applied embodiment of the invention, the well casing, the packing and the connecting bolts being in section, and one half of the support removed,

Figure 2 is a top plan view of the support 40 clamped about a well tubing which is shown in section,

Figure 3 is a perspective view of one-half of the support, the packing being removed, and

Figure 4 is a perspective view of the packing.

Corresponding and like parts are referred to in the following description and designated in the several views of the drawings 50 by like reference characters.

The numeral 1 designates the casing of a well and 2 the tubing for pumping and flowing the well. The support is of circular outline and of a diameter to rest upon the 55 casing 1, and is formed with a central open-

ing of a size to receive the tubing 2. The support comprises similar parts or sections which are adapted to be clamped about the tubing 2 by means of bolts 3.

Each of the sections comprising the support is the counterpart of the other and comprises a semi-circular plate 4 having a depending centering element 5 and an up-standing grip 6 which is internally toothed, as indicated at 7, to bite into the tubing 2 and prevent possible slipping thereof, after the support has been properly applied. The outer side of the centering element 5 is made tapering to enter the casing 1 and its inner side is recessed, as indicated at 8, to receive a packing ring 9 of soft rubber. The inner edge of the plate 4 is likewise recessed, as indicated at 10 to receive opposite extensions 11 of the packing ring 9 to insure a tight joint between the two sections or parts of the support when clamped about the tubing 2. The recesses 10 open into the recess 8, whereby provision is had for receiving the packing ring 9 and its extensions 11.

Ears 12 project outwardly from the up-standing part 6 and are apertured, as indicated at 13, to receive the bolts 3. The ears 12 connect the sides of the part 6 with the plate 4, thereby serving to strengthen and brace the same. The device is further strengthened by means of a brace 14 which is located intermediate the ears 12 and cast with the plate 4 and grip 6.

The packing ring 9 is split and halved, as indicated at 15, thereby admitting of its being fitted about the tubing 2, said ring and its extensions being a trifle larger than the inter-communicating recesses 8 and 10, so that when the sections, or parts of the support are drawn together by means of the bolts 3, the packing will be compressed and insure a tight joint between the support and tubing and between the parts comprising the base.

The invention provides a tubing support, which, as herein stated, comprises in one structure a casing ring and a tubing ring and obviates the necessity for separate slips, since the upstanding parts 6 are adapted to firmly grip the tubing when the parts or sections are drawn together by means of the bolts 3, the teeth 7 preventing any possible slipping of the tubing. The construction is such as to admit of the parts being cast or drop-

forged and the construction is simplified, since one part or section is the duplicate of the other.

Having thus described the invention, I claim:

1. A tubing support comprising similar parts, each consisting of a plate, a centering element depending from the plate, an internally toothed upstanding portion upon the top of the plate in line with the depending centering element and apertured ears at opposite sides of the upstanding portion and forming connecting means between it and the plate.
- 10 2. A tubing support comprising similar parts, each consisting of a plate, a centering element depending from the plate, an internally toothed upstanding portion upon the top of the plate in line with the depending centering element and apertured ears at opposite sides of the upstanding portion and forming connecting means between it and the plate, the inner edge of the plate and the inner wall of the depending portion being recessed for the reception of a packing.
- 15 3. A tubing support comprising similar parts, each consisting of a plate, a centering element depending from the plate, an internally toothed upstanding portion upon the top of the plate in line with the depending centering element and apertured ears at opposite sides of the upstanding portion and forming connecting means between it and the plate, the inner edge of the plate and the inner wall of the depending portion being recessed for the reception of a packing.
- 20 4. A tubing support comprising similar parts, each consisting of a plate having depending and upstanding portions, the latter being internally toothed and the inner edge of the plate and the inner wall of the depending portion being recessed, opposite ears connecting the sides of the upstanding portion with the plate and a brace intermediate the ears and connecting the said upstanding portion with the plate, a packing, comprising a split ring and opposite extensions, adapted to fit within the recessed portions of the plate and the said depending portion and bolts passing through the said ears and serving to clamp the parts about a tubing.

ternally toothed upstanding portion upon the top of the plate in line with the depending centering element and apertured ears at opposite sides of the upstanding grip and forming connecting means between it and the plate, the inner edge of the plate and the inner wall of the depending portion being recessed for the reception of a packing comprising a split ring and opposite extensions to fit within the recessed portions of the sections.

4. A tubing support comprising similar parts, each consisting of a plate having depending and upstanding portions, the latter being internally toothed and the inner edge of the plate and the inner wall of the depending portion being recessed, opposite ears connecting the sides of the upstanding portion with the plate and a brace intermediate the ears and connecting the said upstanding portion with the plate, a packing, comprising a split ring and opposite extensions, adapted to fit within the recessed portions of the plate and the said depending portion and bolts passing through the said ears and serving to clamp the parts about a tubing.

In testimony whereof I affix my signature.

FRANK M. CROWELL. [L.S.]
